UNITED STATES PATENT OFFICE

2,109,750

DOUBLE IDENTITY LIQUID DISPENSER FOR
BOTTLESLeon R. Paul, Brooklyn, N. Y., assignor to John
J. Daly, New York, N. Y.

Application May 15, 1936, Serial No. 79,866

6 Claims. (Cl. 40—4)

The present invention relates to an improvement in advertising liquid dispensing devices for bottled liquids and has for its important feature the provision, on a bottle stopper or cork, of an advertising device, which acts as a mechanical bond for the other coating dispensing and other elements of the structure, thereby obtaining economy in manufacture, the present device being of few simple parts.

10 A further feature of improvement is in the provision of a dual, identifying structure comprising overlaid symbol bearing elements for receiving thereon advertisements, which elements are comparatively easily destroyed and removed, and 15 which when removed without authorization, expose a hidden, permanent advertising notice, which is not easily destructible, but the removal of which will destroy the device, its usefulness being eliminated.

20 The foregoing and other features of advantage will be apprehended as the herein description proceeds, and it will be obvious that modifications may be made in the structure herein, without departing from the spirit hereof or the scope of the 25 appended claims.

In the drawing,

Fig. 1 is a view in elevation of the improved device;

Fig. 2 is a sectional view taken on the line 2—2, Fig. 1, looking in the direction of the arrows;

Fig. 3 is a sectional view taken on the line 3—3 of Fig. 1, looking in the direction of the arrows;

35 Fig. 4 is a view similar to Fig. 3 but showing a mode of mounting a label thereon;

Fig. 5 is a view in elevation of a label holding ring;

Fig. 6 is a transverse sectional view of Fig. 5;

40 Fig. 7 is an enlarged transverse section of the cork cap, taken on the line 7—7, Fig. 8, looking in the direction of the arrows;

Fig. 8 is a plan view of Fig. 7; and

45 Figs. 9 and 10 are enlarged, transverse fragmental sections of the sealing disc, to disclose modified forms of attaching the labels thereto.

As in Fig. 1, the complete pouring device comprises a cork stopper 4, capped by a metal cap 5 having an annular flange 16 thereon, which embraces the top end of the cork 4.

The cork is provided with two through apertures, as is also the cap as at 14, 15, Fig. 8, and the apertures in the cap and cork are in registry to receive therein a liquid pouring tube 2, 55 which is bent at the top to form a turned spout,

the end of which is covered by a pivoted, gravity actuated closing flap, similar to that disclosed in my issued U. S. patent numbered 2,039,658 of May 5, 1936. The present application is also filed in continuation of my application which is developing into Patent Number 2,041,724, having date of issue May 26, 1936.

In the other bore 15 is mounted a venting tube 3, which extends beyond the limits of the cork and cap on both sides thereof and acts to vent a bottle as the liquid is poured from spout 2.

The cork cap 5 as shown in the enlarged views of Figs. 7 and 8 is slightly domed, has flanged perimeter 16 and at its mid-top section is provided with two conjunctive bores 14 and 15, these being formed in said cap by perforating the bores with a blunt tool thereby to form two round apertures of unlike diameter, commonly surrounded by an upstanding ragged toothed flange 12 and 13. The larger bore 14 receives therein 20 and firmly grips the pouring tube 2 in its proper operative position as shown in Fig. 1, while the smaller bore 15 firmly grips therein the vent tube 3 in its operative assembly also as in Fig. 1.

As thus assembled, the cap 5 and its appurtenant tubes 2 and 3, are then laid in a mould or die which holds the assembled tubes and cap in a tight grip.

The die is so made as to be provided with a mould space which surrounds the tubes above the cap, the moulding portion of said die being so contoured as to receive therein a melted plastic metal, which is poured into said mould and is die-casted about said tubes and ragged flange 12—13 of said cap. The final result is as shown in Figs. 1 and 2, in which the sealing disc, generally denoted by 1, is firmly cast or moulded about the tubes and cap flange. Inasmuch as the die metal contracts slightly upon cooling, it thus is assembled in such a manner as to hold all of the assembled parts to itself in a firm embrace.

The mould of the die is provided with legends, either to be cast in intaglio or in relief, which may bear the name of the advertiser or the advertiser's goods on both faces of the disc, as at 10, Figs. 1, 3 and 4.

The sealing disc 1 may also be provided with an integral annulus 8, outstanding on both faces of the disc, and the disc may further have an annular recess 9 at the inner face of the base of flange 8, said recess extending into the faces of said disc, below the plane of said faces, as shown in Figs. 3, 4, 9 and 10, thus to form an encircling groove in which to receive the depending 55

flange 7 of the circular label holding bezel 6, Figs. 5 and 6.

The bezel 6, as shown in Figs. 4 and 9, is used to embrace a paper or cellulosic label 11 about its 5 edges and adjacent edge face, thus to hold the exposed label in operative display position, and covering the moulded-in design 10 on the disc face.

After the bezel and label have been set in display and holding position, the upper outer edge of 10 flange 8 is rolled in slightly as seen clearly in Fig. 9, and thus the bezel and label are firmly gripped in desired display position.

In some instances, where a stiff metallic label is used, as at 11, Fig. 10, the label may be positioned 15 on the disc, and the flange 8 rolled or beaded over the edge of said label.

From the foregoing, it will be seen that the structure and mode of assembly is simple, quite economical and defeats the heretofore tendency 20 of users of the device from destroying the advertising value thereof by removing and destroying the label, and thus losing the identity of the advertiser. To remove any of the labels of the present disclosure brings into view the 25 hidden, permanent advertisement moulded in the metal of the sealing disc 1.

Having thus described the invention what is claimed is:

1. A liquid dispensing device for bottles, comprising the combination of a cork, a flanged cap on said cork, said cap and cork being apertured, 30 a pouring tube and a restricted vent tube mounted in the apertures of said cap and cork, said cap having a flange about said apertures, and a sealing disc moulded about said tubes and said second flange thereby to embrace the cap and tubes in a unit assembly.

2. A liquid dispensing device for bottles comprising, an apertured cork and cap therefor, a 40 pouring tube and a restricted vent tube located in said apertures, a sealing disc moulded about said tubes and a portion of said cap to embrace said tubes and cap in a unit assembly, a label on each face of said disc, said disc having label 45 engaging flanges on its opposite faces to engage said labels in display position and advertising symbols moulded upon the faces of said disc, said labels bearing advertising symbols on their display faces, the symbols on said disc and labels being of like identity.

3. A device including in combination a bottle stopper having mounted in edgewise relation on the top thereof a relatively thick disc, venting and pouring tubes passing through the stopper and the disc, the pouring tube having a discharge end above the disc, said disc having display indicia permanently incorporated in its opposite sides; and thin destructible discs mounted on said sides and having like indicia thereon, said thin discs being intended not to be removed, whereby 10 if the thin discs be wrongly removed the indicia may still appear on the device.

4. A liquid dispensing device and display means comprising a bottle stopper having spaced prongs rising from the top thereof, a thick disc standing 15 in edgewise relation on the stopper and having the prongs fixedly engaged therein, said disc and the stopper having a pair of parallel bores therein, one of the bores being large and both being inwardly of the prongs; a pouring tube in the 20 large bore and having an upper discharge terminal on one side of the vertical central plane of the device, and a vent tube in the other bore and having a lower terminal on the opposite side of said plane.

5. A liquid dispensing device and display means comprising in combination a bottle stopper having top projections thereon, said stopper having therein a pair of apertures which pass between the projections, pouring and venting tubes disposed in the apertures and having straight parts 30 above the projections, and a relatively thick disc disposed in edgewise relation on the stopper and having display indicia on its opposite sides; said disc being die cast in situ and being positioned in 35 embracing relation with said parts and said projections.

6. A liquid dispensing device for bottles comprising the combination of a capped cork, a 40 pouring spout and a restricted vent tube therein, a sealing disc moulded about said spout and tube, said disc having characters moulded on both faces thereof, annular flanges on the perimeter of both faces, a label on each face and a label holding bezel engaging the edges of each label, said 45 annular flanges being turned to engage the edges of the bezel to hold said labels in display position and to hide said characters on the face of said disc.
